UNITED STATES PATENT OFFICE

2,642,258

PRESSURE-TIGHT STOPCOCK ADAPTER

Bertram M. Stone and Roger Gilmont, Brooklyn,
N. Y., assignors to The Emil Greiner Company,
New York, N. Y., a corporation of New York

Application December 15, 1948, Serial No. 65,355

4 Claims. (Cl. 251—112)

1

The invention here disclosed is an adapter for converting ordinary stopcocks to pressure-tight operation.

Particularly it is concerned with the glass stopcocks such as used by laboratory workers.

The general objects of the invention are to enable an ordinary stopcock to be quickly and easily converted to a pressure-tight stopcock which will be vacuum-tight as well as leakproof, adapting it for these special uses for burets, gas sampling, measuring apparatus and the like.

Special objects of the invention are to accomplish all this with a simple, practical and inexpensive form of device which may be readily applied by the laboratory operator and which when so applied will be wholly effective, reliable and durable.

Further special objects of the invention are to provide this adapter construction in a form consisting of but few parts and taking up but small space so that it may be applied and used in all places where a pressure-tight stopcock may be desired.

Other desirable objects and the novel features of construction, combination and arrangement of parts through which the purposes of the invention are attained are set forth or will appear in the course of the following specification.

The drawings accompanying and forming part of the specification illustrate certain present commercial embodiments of the invention. Structure and arrangement, however, may be modified and changed, all within the true intent and broad scope of the invention, as hereinafter defined and claimed.

Fig. 1 in the drawings is a perspective view showing an ordinary glass stopcock with the end washer removed and the separated parts of the adapter in the relation they are attached to the stopcock;

Fig. 2 is an enlarged broken sectional view of the valve structure and attached adapter.

Fig. 3 is a front elevation, and Fig. 4 a broken sectional view of a modified form of the invention;

Fig. 5 is an enlarged cross section on substantially the plane of line 5—5 of Fig. 4.

In the illustrations there is shown a glass stopcock of conventional design embodying a valve body or shell 3 having a tapered valve seat 4 extending therethrough, rotatably receiving the 50 tapered valve plug 5.

The latter is shown as having an operating handle 6 at the outer, operating end and as having the smaller end portion of the same 7, projecting beyond the inner end of the valve body

and provided with an annular groove 8 approximately in line with the end of the valve body.

Normally in this type of valve a rubber or other washer engaged in this groove serves to retain the valve plug in its seat.

In the present invention use is made of the last described features of construction to apply a force for holding the plug seated pressure-tight in the valve body.

10 Specifically there is provided a clutch element shown in the form of an annulus 9 to surround the extended end portion 7 of the valve plug and having an annular flange 10 at the inner end of the same to enter the annular groove 8.

15 To enable engagement of this clutch collar over the end of the valve plug, it is shown as made in relatively separable parts, produced in the first illustrated example, Fig. 1, by longitudinally splitting the same as indicated at 11.

20 The longitudinal pull required to hold the valve firmly in its seat is applied in the first illustration by forming the clutch collar with a longitudinally extended stem 12, screw threaded at 13 to receive the tensioning and locking nuts 14, 15, which serve to provide the outer abutment for the valve holding spring 16.

25 The latter is shown as surrounding the stem portion of the clutch sleeve and as interposed between the inner abutment nut 14 and the closed or flanged outer end 17 of the abutment collar 18, surrounding the split clutch sleeve and bearing against the end of the valve body.

30 In this fashion the expansion force of the spring as applied against the end of the valve body is utilized to draw the valve plug longitudinally into and hold it firmly seated in the valve body, and this without interfering with free, intended rotation of the valve plug.

35 40 The magnitude of this holding force may be determined by adjusting the abutment nut 14 and when the desired tension is attained it may be fixed at this point by tightening the lock nut 15. The clutch collar may turn with the valve plug or may remain stationary while the plug rotates, the annular form of connection between the valve plug and clutch collar at 8, 10, allowing for such operation.

45 The abutment sleeve 18 is free to rotate and so under certain conditions may turn with the valve plug, the several possibilities mentioned being largely determined by the tension applied by the coupling spring 16.

50 55 The device is of simple construction, consists of but few parts and can be quickly and easily applied without the need of any tools, to any ordi-

nary stopcock of the type here under consideration.

The adapter keeps the valve leakproof under any and all conditions of pressure and vacuum and is of advantage further in acting as a drag to guard against accidental turning and to hold the valve in any position to which it may have been carefully adjusted.

The one-piece form of construction of the clutch collar and screw stem is for many purposes preferred. The split at 11 does not extend the full length of the screw stem, leaving the parts integrally connected but free to be laterally opened and closed into engagement over the grooved end of the valve plug.

The abutment sleeve, when it is placed over the clutch sleeve, prevents the latter from opening up and becoming disconnected from the valve plug. The nuts 14, 15, applied to the split screw stem further have this same effect of holding the clutch collar closed on the valve plug. If desired, the parts may be so designed that the clutch jaws will be gripped non-rotatably on the valve plug and hence positively turn with the valve.

In the second form of the invention illustrated in Figs. 3, 4 and 5, the screw is made up as an element separate from the clutch collar and the latter is made in two semi-annular segments engageable laterally over the head of the screw and about the grooved end of the valve plug.

The two separate segments of the clutch collar are illustrated at 9a, having inwardly directed flange segments 10a at their inner ends entered in the groove 8 of the valve plug, and inwardly extending flange segments 20 at their outer ends engaged about the shank portion 21 of the screw 22 and providing an abutment for the head 23 of such screw.

To hold the screw in non-rotatable relation to the clutch segments, said screw is shown as having a transverse pin 24 driven therethrough and disposed in the gap 25, Fig. 5, between the opposing edges of the clutch segments.

The shank portion 21 of the screw may be annularly grooved as indicated at 26 in Fig. 4, directly in back of the head 23, to receive the inner edges of the flange segments 20, thus to hold the screw in position with the cross pin 24 engaged in the slot 25 between the companion segments. This is to aid in assembling the parts.

The abutment sleeve 18, when it is applied over the screw and clutch segments, retains the parts in properly assembled relation, the same as in the first described form of the invention.

By making the screw separate from the clutch collar as last described, several advantages are attained. In particular, the same size screw may be used for any number of different size adapters. The clutch segments 9a may be made up in duplicate parts inexpensively stamped out of sheet metal for different size valve plugs. This two-part clutch collar may be considered as easier to assemble since the companion clutch members are entirely separate and may be put on independently over the opposite sides of the valve plug.

What is claimed is:

1. In combination with a stopcock including a valve body and a valve plug journaled therein and having an end portion projecting beyond the end of the valve body and provided with an annular groove, a pressure-tight adapter for converting the same to pressure-tight operation, comprising a clutch collar having an inwardly extending portion for engagement in the annular groove in the projecting end portion of the valve

plug, an abutment sleeve surrounding said clutch collar arranged to bear against the end of the valve body, said sleeve having an abutment wall at the outer end of the same beyond the clutch collar, a screw element extending from the clutch collar beyond said abutment wall, an abutment nut on the outer end of said screw element and a valve seating spring about said screw element between said abutment wall and abutment nut, 10 said clutch collar being made in separate, companion parts independently engageable over the opposite sides of the valve plug and said screw element being separate from said clutch parts and having a head held between the companion clutch parts.

2. In combination with a stopcock including a valve body and a valve plug journaled therein and having an end portion projecting beyond the end of the valve body and provided with an annular groove, a pressure-tight adapter for converting the same to pressure-tight operation, comprising a clutch collar having an inwardly extending portion for engagement in the annular groove in the projecting end portion of the valve plug, an abutment sleeve surrounding said clutch collar arranged to bear against the end of the valve body, said sleeve having an abutment wall at the outer end of the same beyond the clutch collar, a screw element extending from the clutch collar beyond said abutment wall, an abutment nut on the outer end of said screw element and a valve seating spring about said screw element between said abutment wall and abutment nut, 25 said clutch collar being made in separate, companion parts independently engageable over the opposite sides of the valve plug and said screw element being separate from said clutch parts and having a head held between the companion clutch parts and said screw element having a transverse key disposed between the opposing segments of said clutch collar.

3. In combination with a stopcock including a valve body and a valve plug journaled therein and having an end portion projecting beyond the end of the valve body and provided with an annular groove, a pressure-tight adapter for converting the same to pressure-tight operation, comprising a clutch collar having an inwardly extending portion for engagement in the annular groove in the projecting end portion of the valve plug, an abutment sleeve surrounding said clutch collar arranged to bear against the end of the valve body, said sleeve having an abutment wall at the outer end of the same beyond the clutch collar, a screw element extending from the clutch collar beyond said abutment wall, an abutment nut on the outer end of said screw element and a valve seating spring about said screw element between said abutment wall and abutment nut, 40 said clutch collar being made in separate, companion parts independently engageable over the opposite sides of the valve plug and said screw element being separate from said clutch parts and having a head held between the companion clutch parts and said screw element having a transverse key disposed between the opposing segments of said clutch collar.

4. In combination with a stopcock including a valve body and a valve plug journaled therein and having an end portion projecting beyond the end of the valve body and provided with an annular groove, a pressure-tight adapter for converting the same to pressure-tight operation, comprising a clutch collar having an inwardly extending portion for engagement in the annular groove in the projecting end portion of the valve plug, an abutment sleeve surrounding said clutch collar ar-

ranged to bear against the end of the valve body, said sleeve having an abutment wall at the outer end of the same beyond the clutch collar, a screw element extending from the clutch collar beyond said abutment wall, an abutment nut on the outer end of said screw element and a valve seating spring about said screw element between said abutment wall and abutment nut, said screw element being transversely grooved and said clutch collar being in transversely separable segments 10 having inwardly extending segmental flanges at the outer end of the same engaged in the transversely grooved portion of said screw.
